UNITED STATES PATENT OFFICE.

PHILLIP J. BAUR, OF PHILADELPHIA, PENNSYLVANIA.

CONFECTIONERY MACHINERY.

1,272,892.

Specification of Letters Patent. Patented July 16, 1918.

Application filed November 15, 1917. Serial No. 202,168.

To all whom it may concern:

Be it known that I, PHILLIP J. BAUR, a citizen of the United States of America, residing at 2335 Sedgley Ave., Philadelphia, in the county of Philadelphia and State of Pennsylvania, have invented certain new and useful Improvements in Confectionery Machinery, of which the following is a specification.

10 This invention relates to confectionery machinery and in its more intense aspect to a machine or apparatus particularly adapted for use in cutting cake.

15 One of the objects of the present invention is to provide a simple and practical apparatus of the above general character designed to cut cake or the like without breaking the same. A further object is to provide a reliable and efficiently operating machine 20 of the above character which will be inexpensive to manufacture, install and operate. A further object is to provide a cutting machine of the above general character with means for keeping the instrumentalities clean.

25 Other objects will be in part obvious from the annexed drawings and in part indicated in connection therewith by the following analysis of this invention.

30 This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and 40 relation contemplated by this invention, drawings depicting a preferred form have been annexed as a part of this disclosure, and in such drawings, like characters of reference denote corresponding parts throughout all the views, of which:

45 Figure 1 is an end elevational view of such parts of the machine as are necessary to fully understand the present invention;

50 Fig. 2 is a side elevational view on a slightly reduced scale.

55 Referring now to the drawings in detail, 5 denotes a framework or table of general rectangular shape having mounted in its lower part a motor 6 adapted to be controlled by a switch mechanism 7 housed in a suitable casing 8. This motor is adapted

to drive, through a belt 10, a wheel 11 on a shaft 12 which in turn is connected by means of belt 13 with a main pulley 14 on a main driving shaft 15. This driving shaft is provided at each end with relatively large wheels or pulleys 16 and 17 about which passes cutting instrumentalities or band blades 18 and 20 respectively. These endless band blades pass over pulleys 21 and 22 mounted upon suitable stub axles or shafts in bearings 23 on the upper part of the frame. Lubricating devices 24 are positioned as indicated.

60 These shafts or rather the bearings 23 therefor are trunnioned at 25 in brackets 26 in the laterally extending arms of which are screws 27 engaging the rear ends of the bearings or journals. Thus by operating the screws 27, the wheels may be adjusted 65 about their trunnions 25 to increase or decrease the tension upon the band cutting instrumentalities.

65 The shaft 15 is provided at one end with a sprocket 30 meshing with a sprocket chain 31 passing over a second sprocket 32 upon a shaft 33. This shaft 33 is provided with a beveled gear 34 at its end adapted to mesh with a second beveled gear 35 on a transverse shaft 36. This shaft carries two relatively large rollers 37 about which pass two 70 endless belts 38, the opposite ends of which belts pass over pulleys 40 mounted in bearings 41 which may move longitudinally by means of adjusting wheel 42, thereby to vary 75 the tension of these belt conveyers. It will be noted by reference to Fig. 1, that the band saws 18 and 20 pass between these endless belt conveyers 35.

80 At the opposite side or rear of the machine are two pairs of disks 43 mounted upon a shaft 44 having cork inserts, as shown in Fig. 2, whereby as they revolve relative to the band blades they will clean and polish the same. Both pairs or sets of 85 these disks are driven by means of an endless belt 45 driven from a pulley wheel 46 on the main shaft 15. One part of the belt passes over guide pulley 47, thence over pulley 48 to the opposite set back over guide 90 pulleys 50 and 51 to the driving pulley 46. The disks 43 dip into a tank 49 containing 95 water and revolve in a direction opposite to the motion of the blades thereby to clear and scour them. The corks are cheap, they 100 wear well and efficiently and may be easily replaced.

Above the conveyers 38 is a small table 52 having an attachment 53 thereon adapted to collect any water or crumbs that may adhere to the band blades after passing the cleaners 43.

It is believed that the construction is clear from the above and the operation thereof is substantially as follows: The cakes which are in relatively large squares are placed 10 upon the belt conveyers 38 at one end and carried past one band blade which cuts the cake through the middle. An operator stands opposite the center of the table and as the cakes reach that point they are turned 15 by hand at right angles and as they continue their movement are cut again by the second band blade. They are removed at the end of the conveyer either by hand or automatically as desired. The adjustments in 20 tension may be made as necessary and the speed of the machine controlled by the single operator.

From the above, it will be seen that the present invention provides a simple, practical cutting machine, particularly adapted 25 for operation upon the cake, although it is, of course, to be understood that other materials may be operated upon thereby.

Without further analysis, the foregoing 30 will so fully reveal the gist of this invention that others can by applying current knowledge readily adapt it for various applications without omitting certain features that,

from the standpoint of the prior art, fairly constitute essential characteristics of the 35 generic or specific aspects of this invention, and therefore such adaptations should and are intended to be comprehended within the meaning and range of equivalency of the 40 following claims.

I claim:

1. In an apparatus of the character described, in combination, a supporting frame, a conveyer, an endless cutting instrumentality, pulleys therefor, a single driving means 45 for operating the conveyer and cutting instrumentality, and means for varying the tension of said cutting instrumentality comprising a tilting journal box for one of the pulleys, and means for tilting the same about 50 a line transverse to the axis of said pulley and at one side thereof.

2. In an apparatus of the character described, in combination, a frame, an endless cutter, and means for cleaning said cutter after the cutting operation including a pair of disks disposed at opposite sides of the cutter having cork inserts adapted to clean the same as it passes therebetween.

In testimony whereof I affix my signature in the presence of two witnesses.

PHIL J. BAUR.

Witnesses:

G. A. BROWN,
ANNA M. MILLER.
